UNITED STATES PATENT OFFICE.

PARKER WELLS, OF LYNN, MASSACHUSETTS.

SPEED-GOVERNOR.

SPECIFICATION forming part of Letters Patent No. 271,288, dated January 30, 1883.

Application filed July 24, 1882. (No model.)

To all whom it may concern:

Be it known that I, PARKER WELLS, a citizen of the United States, residing at Lynn, State of Massachusetts, have invented certain new and useful Improvements in Speed-Governors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to governors or regulators for steam-engines, the device being adapted to govern both feed and speed; and the novelty consists in the construction and arrangement of parts, as will be more fully hereinafter set forth, and specifically pointed out in the claims.

The device is designed as an improvement upon or variation from the construction set forth in an application for a patent for a device having the same objects in view, filed of even date with this; and the object of the invention is to produce a governor or regulator which shall be simple and cheap of construction, efficient in service, and not liable to get out of order. It also provides for economy of room in reducing the length of the ordinary revolving vertical shaft. In the patent referred to wrenching and binding on *c* may occur, and to give the free action to the balls, in this device it is proposed to give the balls a free action within proper guides.

The invention is fully illustrated in the accompanying drawings, which form a part of this specification, and in which—

Figure 1 is a side elevation, partly broken away to show the arrangement of the steam-ports; Fig. 2, a detail of slotted cylinders in which the balls operate, and Fig. 3 a modification.

To enable others skilled in the art to which the invention relates to make and use the same, I will describe the construction and mode of operation, referring for that purpose to the said drawings, in which similar letters of reference indicate like parts in all the figures.

A represents the revolving governor-shaft, having threaded end *a* upon the upper extremity, and a beveled gear, *a'*, at the lower

extremity, which gear *a'* meshes with a similar gear, *b*, upon a horizontal shaft, *B*, carrying a pulley, *b'*, which receives its power from the engine over which the governor herein described exercises control. The vertical shaft *A* revolves in a sleeve, *x*, rigid with a suitable frame, *x'*, around which operates loosely a sleeve, *C*, having an annular recess in its circumference, in which operates a fork connected with a crank-lever secured to a valve-frame which operates loosely in a port-cylinder, the said port-cylinder being inclosed in a suitable steam-tight case, having steam-inlet from the boiler and steam-connection with the steam-chest or piston-cylinder, as shown. These parts are fully set forth in another application, and form no part of this invention.

The invention is embodied in the parts hereinafter described.

Rigid with the vertical shaft *A* is an arm, *E*, extending outwardly from opposite sides, each of said arms carrying a cage or cylinder, *F*, in which operates the ball *D*, pivoted by a yoke, *C'*, to an arm, *C*, which in turn is pivoted at *c* to the sleeve *C*. The centrifugal force of the balls *D* is resisted by a spring, *G*, which is rendered adjustable by means of a thumb-nut, *g*, acting upon the threaded part *a*. In relation to the spring, I prefer the construction shown in Fig. 3, in which not only is the spring *G* adapted to be adjusted by nut *g* in relation to the speed sought to be attained, but that spring *G* is further adjusted by an auxiliary spring, *G'*, similarly adjustable upon the part *a* by means of the nut *g'*. This compound-spring action may be employed in connection with the cage or cylinder *F*, as shown in Figs. 1 and 2, or with a horizontal arm, *E E*, as shown in Fig. 3.

It is obvious that the elevation or depression of the nut *g* or *g'* will regulate the steam-pressure upon the piston, and consequently the speed of the engine.

The engine, when at rest, allows the sleeve *C*, balls *D*, &c., to assume their lowest gravitational point, and in this condition the ports in the valve-cylinder and port-cylinder correspond and an equal pressure exists. When, however, steam is admitted from the boiler, such steam passing freely to the piston-cylinder and acting to start the engine with full power, the

centrifugal force, acting upon the balls D, elevates the sleeve C, which action closes or partially closes the steam-ports between the port-cylinder and the valve-cylinder, while at the same time the resisting spring-force of the ogee spring G, governed by the constant and adjustable force of the auxiliary spring G', serves to afford a medium between the steam feed and pressure, as the same is controlled by the speed of the engine, counteracted by the influence of the governor-valve.

It will also be observed that if a high rate of speed is required the nut g' may be screwed down upon the part a to force the free ends 15 of the spring G inward upon the balls, which action will limit the throw of the said balls D, the elevation of the sleeve C, and the consequent capacity of the steam-ports, while if a lower rate of speed is desired the spring-force 20 of both springs G and G' may be regulated in such a manner that the centrifugal force will more readily control the capacity of the ports for inlet of steam.

The points of this invention which are deemed 25 important lie in the cage or cylinder F and

the compound spring G G'. In engine-rooms the economy of space allowed by this construction, is, in many instances, important.

What I claim as new is—

1. The combination of the pulley b', shaft 30 B, and gears b and a', with the sleeve C, balls D, connections C' C², cage or cylinder F, and spring G, as and for the purposes set forth.

2. The vertical shaft A, arms E, balls D, sleeve C, and connections with said balls, combined with the cage or cylinder F, adjustable spring G, and auxiliary spring G', and with the nuts g and g' for regulating speed, as and for the purposes specified.

3. In a steam-governor, the combination of 40 a valve-closing mechanism with a spring, G, adapted to resist centrifugal force, and with an auxiliary adjustable spring, G', adapted to regulate speed at will, as specified.

In testimony whereof I affix my signature in 45 presence of two witnesses.

PARKER WELLS.
